UNITED STATES PATENT OFFICE.

CHARLES BASHWINER, OF JAMAICA PARK, NEW YORK, ASSIGNOR TO YOUNG & MC GUIRE, INC., A CORPORATION OF NEW YORK.

FOLDABLE FRAMED DISPLAY CARD.

Application filed March 5, 1924. Serial No. 696,998.

To all whom it may concern:

Be it known that I, CHARLES BASHWINER, a citizen of the United States, and a resident of Jamaica Park, borough of Queens, in the county of Queens and State of New York, have invented certain new and useful Improvements in a Foldable Framed Display Card, of which the following is a full, clear, and exact specification.

10 This invention relates more particularly to a class of foldable devices for displaying advertisements and kindred subjects.

My invention has for its object primarily to provide an article or card designed to be employed in stores and other public places for displaying especially publicity matter in a manner whereby the attention of persons will be attracted thereto, and which is susceptible of being made of cardboard or other flexible material to permit subject matters to be printed or impressed on one surface thereof and then folded for providing a surface section having a picture or other artistic illustration as well as having a surface section of a type so that the advertisements or other illustrated subjects may be displayed if desired in conjunction with the picture or subjects on the surface section. The invention consists essentially 25 of a flexible blank preferably of card board which is cut, scored and folded to provide an angular surface section for permitting the display on one of its faces of a picture or other subject. At the edges of the surface section are frame members surrounding the illustrated subject, and all of the frame members are formed with corresponding faces disposed on diverging inclines to allow suitable subject matters to be also displayed thereon as occasion requires.

40 A further object of the invention is to provide a foldable framed display card of a simple and efficient formation which may be made in appropriate shapes of various sizes.

With these and other objects in view, the invention will be hereinafter more fully described with reference to the accompanying drawings forming a part of this specification in which similar characters of reference

indicate corresponding parts in all the views, and will then be pointed out in the claims at the end of the description.

In the drawings, Figure 1 is a front elevation of one form of foldable framed display card embodying my invention.

Fig. 2 is a plan of the blank from which the device is formed.

Fig. 3 is an enlarged sectional view taken on the line 3—3 of Fig. 1.

Fig. 4 is an enlarged sectional view taken on the line 4—4 of Fig. 3, and

Fig. 5 is an enlarged perspective view showing the manner of folding the device.

The display card is formed from a blank, 55 as 10, of cardboard or other foldable material which is cut to provide a surface section A and frame members or extending sections B, C, D, E.

The surface section A may be of a suitable angular shape, though the form of this section illustrated is substantially rectangular, and the blank 10 is cut and scored, as at 11, 12, 13, 14, to provide the surface section of the desired dimension. The blank 70 is cut out at the corner parts of the surface section A to provide the members or sections B, C, D, E so that they extend in lateral direction from the edges of the surface section.

The frame members or extending sections B and C are of corresponding shapes and sizes. These members are divided into infold parts 15, 15^a, face portions 16, 16^a, edge parts 17, 17^a and tongues 18, 18^a by 75 scoring the members lengthwise at 19, 19^a, 20, 20^a, 21, 21^a respectively. The edge parts 17, 17^a and the tongues 18, 18^a of the frame members B and C are approximately similar in lengths to the lengths of the edges 11 and 12 of the surface section A. The infold parts 15, 15^a are shorter than the edge parts 17, 17^a and the tongues 18, 18^a, and the ends of the face portions 16, 16^a are thereby cut on inclines, as at 22, 22^a and 23, 23^a respectively.

The frame members or extending sections D and E are also of similar sizes and shapes, and these members are divided into infold parts 24, 24^a, face portions 25, 25^a, edge 85 100

parts 26, 26^a and tongues 27, 27^a by scoring the members lengthwise respectively, at 28, 28^a, 29, 29^a, 30, 30^a. The members D and E are preferably similar in lengths to the lengths of the edges 13 and 14 of the surface section A. In the ends of the face portions 25 of the frame member D may be two notches, as 31, 31^a, and in the ends of the face portion 25^a of the frame members E 10 may be two notches, as 32, 32^a. Projecting in opposite directions from the ends of the edge part 26 of the frame member D may be two hook-shaped members, 33, 33^a, and protruding in opposite directions from the ends 15 of the edge part 26^a of the frame member E may also be two hook-shaped members 34, 34^a. The hook members 33, 33^a are adapted to be removably inserted in the notches 31, 31^a of the frame member D, and the hook 20 members 34, 34^a are adapted to be removably inserted in the notches 32, 32^a of the frame member E. On one face of the surface section A of the blank 10 may be printed or impressed a picture of other illustrated subject, as 35, and on the face portions 16, 16^a 25 and 25, 25^a of the corresponding surface of the blank may also be printed or impressed appropriate advertisements or other subject 30 matters, as 36.

When the display card is formed the blank 10 is folded on the scorings 13, 14 and 28, 28^a and the infold parts 24, 24^a of the frame members D and E are then disposed so that they overlap the surface section A on which is displayed the picture 35. The frame members D and E are folded on the scorings 29, 29^a and 30, 30^a. The face portions 25, 25^a are disposed on diverging inclines from the surface section A, and the edge parts 26, 26^a of the frame members are disposed from the inclined face portions toward the surface section at rightangles relative to two of the opposite edges of the surface section. The hook-shaped members 33, 33^a and 34, 34^a are inserted in the notches 31, 31^a and 32, 32^a of the frame members D and E for releasably locking together the face portions 25, 25^a to the edge parts 26, 26^a of these frame members. The tongues 27, 27^a 40 are then folded inwardly upon the infold parts 24, 24^a which overlap the surface section A. The blank is afterward folded on the scorings 11, 12 and 19, 19^a, and the infold parts 15, 15^a of the frame members B and C are disposed so that they overlap the surface section A on which is shown the picture 35. The frame members B and C are folded on the scorings 20, 20^a and 21, 21^a. The face portions 16, 16^a are then disposed 45 on diverging inclines from the surface section A, so that the ends of the face portions 16, 16^a overlap the ends of the face portions 25, 25^a of the folded frame members D and E. The edge parts 17, 17^a of the frame members D and E are disposed from the in-

clined face portions 16, 16^a toward the surface section at rightangles relative to the second opposite edges of the surface section. The tongues 18, 18^a are then folded inwardly to lap upon the infold parts 15, 15^a that overlap the surface section, and the inner edges of these infold parts 15, 15^a may then be adhesively secured by glue, as indicated in dotted lines at 37, 37^a, to the surface section A. The illustrated subjects 36 on the face portions 16, 16^a 25, 25^a will appear on the exposed surfaces of the face portions without requiring the blank 10 to be printed or illustrated on both of its faces.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:—

1. A framed display card cut and folded from a single blank, comprising a substantially rectangular surface section having on its edge parts overlapping frame members, all with corresponding faces disposed on diverging inclines from one face of the surface section, and all the frame members having edge parts disposed from the inclined faces to the surface section rightangularly thereto, two of the opposite frame members having the ends of their faces and edge parts releasably locked together and the second two opposite frame members secured to the surface section.

2. A framed display card cut and folded from a single blank, comprising a substantially rectangular surface section having on its edge parts overlapping frame members, all with corresponding faces disposed on diverging inclines from one face of the surface section and all the frame members having edge parts disposed from the outermost edges of the inclined faces to the surface section rightangularly thereto, two of the opposite frame members having the ends of their faces and edge parts releasably locked together and the end portions of the second two opposite frame members overlapping the locked ends of the other frame members.

3. A framed display card cut and folded from a single blank, comprising a substantially rectangular surface section having on its edge parts overlapping frame members, all with corresponding faces disposed on diverging inclines from one face of the surface section and all of the frame members having edge parts disposed from the outermost edges of the inclined faces to the surface

section rightangularly thereto, interfitting members releasably locking together the ends of each of two of the opposite frame members overlapping the locked ends of the other frame members, said pair of overlapping frame members adhesively secured to the surface section.

This specification signed and witnessed this 4th day of March A. D. 1924.

CHARLES BASHWINER.
